P. C. LOWTHORP.
Testing Apparatus.

No. 17,383.

Patented May 26, 1857.

UNITED STATES PATENT OFFICE.

FRANCIS C. LOWTHORP, OF TRENTON, NEW JERSEY.

HYDRODYNAMIC MACHINE FOR TESTING STRENGTH OF MATERIALS.

Specification of Letters Patent No. 17,383, dated May 26, 1857.

To all whom it may concern:

Be it known that I, FRANCIS C. LOWTHORP, of the city of Trenton, in the county of Mercer and State of New Jersey, have invented 5 certain new and useful Improvements in Machinery for Testing the Strength of Materials; and I do hereby declare the following to be a full, clear, and exact description of the same, reference being had to the accompanying drawing and to the letters of 10 reference marked thereon.

My invention relates to machinery for ascertaining the amount of tensile or transverse strain, or torsion, or crushing force 15 which materials are capable of withstanding, and consists in so combining suitable gearing and other mechanism, for applying said strains or forces, with a piston or plunger operating against a body of water or 20 other suitable fluid, within a cylinder or barrel, that on applying the force or strain to the object to be tested, by the gearing, such a pressure shall be transmitted to the fluid in the cylinder or barrel, and to any 25 suitable indicating apparatus in connection with the same, as to enable the attendant to readily calculate the amount of strain or force to which the object has been submitted.

My invention has for its aim the testing 30 of a succession of objects with greater ease and rapidity than the same can be accomplished by hydraulic rams, complex levers, and other cumbrous and tedious appliances hitherto used for the same purpose.

35 In order to enable others skilled in the art to make and use my invention I will now proceed to describe its construction and operation.

On reference to the drawing which forms 40 a part of this specification, Figure 1, represents a side view of my improved testing apparatus; Fig. 2, a ground plan of the same; Fig. 3, an end view looking in the direction of the arrow 6 (Fig. 2,); Fig. 4, 45 a section on the line 1, 2, (Fig. 2,) and Fig. 5, an end view looking in the direction of the arrow 7 (Fig. 2).

Similar letters refer to similar parts throughout the several views.

50 Two substantial beams, one composed of the longitudinal pieces A, B, and C and the other of the pieces A', B', and C' are placed a suitable distance apart and connected together by the cross pieces D, D' and D² and stayed by the diagonal braces b, b, b, b. The

intermediate pieces B and B' are narrower than the upper and lower pieces in order that a groove may be formed on the inside of the two main beams. Across the opposite end of these beams are secured the upper beam E and lower beam F and to the former are secured two longitudinal beams G and G' to the end of which is attached another cross piece H of the same size and form as E, the inner ends of the pieces G and G' 60 being secured to the cross piece I, which, together with a similar piece J is secured to the main beams. On the cross pieces I and J is erected a light framework composed of the uprights e and e' and cross piece f. 65 The above forms the framework of the apparatus which may be extended to any length desired.

Near one end of the frame and between the two main beams is firmly secured a cylinder K the center line of which coincides with the center of the grooves on the inside of the beams. This cylinder is bored out perfectly true and is furnished with covers g and g', piston, stuffing box h, and piston rod L, all constructed and arranged similar to those of an ordinary steam engine. 75

On the top of the cylinder are two orifices i, and i' one communicating with the interior of the cylinder on one side of the piston and the other with the interior of the cylinder on the opposite side of the piston so that the pipe j which communicates with the pressure gage M, on the cross piece f, may be attached to one or other opening, the indicator being so arranged on the cross piece as to be readily removed from a position above one opening to that above another. On the top of the cylinder and communicating with the interior of the same, on opposite sides of its piston, are two openings k and k' for the admission of air and water as hereafter set forth. 85 90 95

To the piston rod L is firmly secured a cross head N having hubs at each end which slide in grooves on the inside of the opposite main beams, as seen at Fig. 4. In the hubs of this cross head fit the shafts O and O' supplied on each side of the hubs with collars so that they may turn freely but have no longitudinal movement independent of the crosshead and piston rod. Toward the ends of the shafts O and O' are cut screws adapted to similar screws cut in the hubs at the end of the cross head P, which is also 100 105 110

arranged to slide in the grooves on the inside of the main beams. A spur wheel Q with a pinion R attached turns loosely on the piston rod L, the pinions S and S' gearing into the wheel Q and the wheels T and T' into the pinion R. The wheels T, and T' are secured respectively to the screw shafts O and O' and into these wheels gear the pinions m and m' on the shafts n and n'

10 which turn in boxes p and p' secured to the underside of the beams E and H. The ends of the shafts u and u' are n and n' are squared for the purpose of receiving suitable handles by which they may be turned. The pinions S and S' and m and m' may be either sufficiently broad to remain always in gear with the wheels during the lateral movement of the latter in connection with the piston rod, and screw shafts; or may 15 otherwise be arranged to slide on their shafts. Another crosshead V is arranged to slide with its opposite ends in the grooves of the main beam and is securely confined to the desired position by means of the keys 20 W, W, which fit into slots cut perpendicularly into the main beams which are perforated with similar slots at different intervals throughout the length in order that the position of the crosshead may be changed 25 to suit the object to be tested.

The two cross heads V and P have oblong holes passing entirely through them and at right angles to these are round holes for the reception of the pins q, q as seen in Fig. 5.

30 Supposing it be required to test the tensile strain of the rod X as well as the strength of the eyes at each end of the same. The crosshead V having been secured to its proper position by means of the keys W and the eyes of the rod X inserted into the oblong holes in the cross heads and secured thereto by pins q, the cylinder K being supplied with water between the piston and cover g, and that water being in communication through the pipe j with the pressure gage M, the orifice k being closed and either or both of the orifices i' and k' open, and the pinions S and S' in gear with the wheel Q the machine is ready to be put in operation.

35 Supposing the rod X to have a sectional area of one inch and it be required to test it to a tensile strain of ten tons to the inch, and supposing the cylinder to be 20 inches in diameter or (say) an area of 314 inches and the pressure gage to be marked on the face to represent pounds. The attendant or attendants turn either one or both of the shafts V or V' in the direction of their arrows, this through the wheel Q, pinion R and wheels T and T' causes the screw shafts O and O' to turn in the direction of their arrows, and these screws having right handed threads it is evident that the cross-

head N submitting the rod X to a tensile strain which increases as the wheels continue to be turned.

Should the pointer on the face of the pressure gage reach 100 lbs. it is evident the strain on the rod will be one hundred times the area of the cylinder, which we have already supposed to be 314 inches, so that the strain would be thirty one thousand four hundred and sixteen pounds, or about ten tons.

When it is desirable to ascertain the amount of compression which materials will withstand, the crosshead V is secured in proximity to the crosshead P the pipe j of so the indicator connected to the orifice i', the orifice k' closed and the orifices i and k remaining open, the wheels are turned in a contrary direction to that pointed out by their arrows causing the crosshead P to approach the crosshead V compressing the intervening material until the amount of compression is designated by the pointer of the pressure gage as before.

The facility with which materials can be submitted to a transverse strain by the above apparatus will be readily understood without further explanation.

The rod having been tested the wheels are turned in a direction contrary to that pointed out by the arrows which causes the crosshead P to approach the crosshead V when the pins q, q, are removed and the tested rod replaced by another. In order to facilitate the movement of the screw shafts during certain portions of their operation the handles are changed from the shafts U and U' to the shafts n and n' and as the pinions m and m' gear directly into the wheels T and T' it is evident that the movements must be more rapid than before. When it is desirable to ascertain what amount of torsion or twisting strain a shaft 3 is capable of bearing, I secure it to blocks 2 which are firmly attached to the opposite main beams, and partially surrounding the wheel 4 which is also secured to the shaft with a chain to the end of which is connected the crosshead P, the wheels are turned as before until the pressure of the water in the cylinder moves the pointer of the pressure gage to the required mark, the leverage afforded by the wheel 4 being taken into consideration.

It will now be seen that objects may be acted upon by my improved apparatus in much more rapid succession than by complex arrangements of screws and levers, hydraulic rams, and other contrivances for effecting the same object.

I do not desire to confine myself to the precise form of the framework or to the material of which it is constructed, to the precise arrangement of gearing shown, or to any particular construction of indicator, inasmuch as the frame may be of any length,

width, or shape to suit the objects to be tested, may be made of iron instead of wood, as the system of gearing may be modified without altering the result, and as a weighted valve or other indicator may be used instead of a pressure gage, but

What I claim and desire to secure by Letters Patent is,

The combining of gearing and other suitable mechanism for applying strains or forces to the object to be tested, with a piston or plunger operating against a body of water within a cylinder or barrel in such a

manner that on applying the said force or strain, such a pressure shall be transmitted to the fluid and to any suitable indicator communicating with the same that the amount of strain or force on the object may be readily calculated.

In testimony whereof I have signed my name to this specification before two subscribing witnesses.

F. C. LOWTHORP.
